UNITED STATES PATENT OFFICE.

NICOLA D'ANDREA, OF BRIDGEPORT, CONNECTICUT, ASSIGNOR OF ONE-HALF TO
MICHAEL PERSICHINO, OF BRIDGEPORT, CONNECTICUT.

REPAIR TIP FOR SHOES.

1,422,543.

Specification of Letters Patent. Patented July 11, 1922.

Application filed January 25, 1922. Serial No. 531,801.

To all whom it may concern:

Be it known that NICOLA D'ANDREA, a subject of the King of Italy, and resident of Bridgeport, in the county of Fairfield and State of Connecticut, has invented certain new and useful Improvements in Repair Tips for Shoes, of which the following is a specification.

This invention relates to a novel repair tip for shoes.

An object of the invention is to provide an improved repair tip, of very simple construction, ready for attachment to the toe of a shoe requiring to be repaired.

A further object is to provide a repair tip which can be readily shaped to nicely fit the vamp of a shoe.

A still further object is to provide an article of manufacture of the present character which can be placed upon a shoe of any construction, as a substitute for a damaged tip, in such manner that the welt of the repair tip and the ordinary welt of the shoe will align, whereby the repaired shoe will be entirely slight and neat, and whereby one continuous row of stitching through the extending portions of the welts of both the tip and shoe will be possible.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and meant to in no way limit the spirit of the invention, changes in details of construction and arrangement of parts being permissible so long as within the scope of the appended claims.

In the accompanying drawing forming a part of this specification.

Fig. 1 is a top plan view of a shoe embodying the features of the invention;

Fig. 2 is a sectional view as on line 2—2 in Fig. 1, looking in the direction of the arrows;

Fig. 3 is a sectional view as on line 3—3 in Fig. 2, looking in the direction of the arrows; and

Fig. 4 is a view corresponding with the showing of Fig. 3, but disclosing a slightly modified form of the invention.

In the drawing, 10 denotes the vamp of

a shoe requiring repairing, 11 the welt attached to the vamp in usual fashion and extending at opposite sides of the shoe, and 12 represents the shoe heel. For the sake of clearness the vamp and heel are shown in dotted lines and the shoe welt is shown in full lines.

The repair tip is constituted by a cap 13 having its lower edges turned in as at 14, and a welt 15 secured to the under face 65 of the turned in portion of the toe cap as by means of clench nails, pegs or stitching 16.

The repair tip of the invention may be applied to a shoe in the following manner. The damaged tip of the shoe and the half sole 17 thereof may be first removed, 18 denoting the forward edge of the upper portion of the vamp, 19 the forward edge 70 of the inturned portion of the vamp, and 20 denoting the forward edge of the shoe welt. The tip may be then associated with the vamp, its inturned portion, and the shoe welt as best shown in Fig. 2. That is, the toe cap 13 may be slipped over the forward 75 edge 18 of the vamp, the inturned edge 14 of the toe cap may be made to align with or fit beneath the inturned edge 19 of the vamp, and the rear edge of the welt 15 of the tip, which will naturally align with the 80 welt 11 of the shoe, may be of proper length to be contiguous with the forward edge 20 of said shoe welt. Numeral 21 denotes holes in the rear edge of the toe cap by means of which the cap may be sewed to 85 the forward portion of the vamp. Obviously, as the shoe welt 11 and the tip welt 15 align with each other and are contiguous with each other, a single continuous 90 row of stitching, not shown, may be employed to secure the half sole 17 to both of said welts, the stitching, naturally, as is usual, being received by the extending portions of both of said welts. Or, clench nails or pegs may be utilized for securing the 100 half sole to the welts in customary fashion.

In Fig. 4 I have suggested how the repair tip of Fig. 3 can be adjustable to fit a shoe even though the vamp has become mis-shaped by wear. An inspection of Fig. 105 4 will show that the clench nails, pegs, or stitches 16 are arranged only at or adjacent the forward portion of the toe cap and repair tip welt, leaving the rearward portions of the repair tip free to be ad- 110

- justed. That is to say, the rear ends of the toe cap can be moved toward or from each other and the turned in edges 14 thereof can be made of greater or less dimensions to fit the cap to a vamp, and the forward portions of the shoe tip welt 15 can be adjusted toward or from each other so that the outer edges thereof can be made flush with the outer edges of the shoe welts.
- 10 The present shoe tip can be placed upon a shoe upper or vamp independently of the insole of the shoe. In cases where the insole is damaged, as well as the tip, it will be removed as the damaged tip is removed. In 15 cases where the insole is not badly damaged, it will be situated adjacent the in-turned edges of the repair shoe cap in about the manner it was situated in the cap of the damaged tip.
- 20 While I have described the novel shoe tip as a repair tip, it is to be understood that this tip can be utilized in the manufacture of new shoes as well as in the repair of old shoes. Evidently, the repair tips can 25 be made in any sizes.
- I have described one particular manner in which the improved tip can be attached to a shoe. It will be apparent that there are other ways in which the attaching can 30 be done. The relative positions of the rear edges of the toe cap and the repair tip welt, and the forward edges of the shoe vamp, the turned in part thereof, and the shoe welt may be as shown, or the parts mentioned 35 may bear to each other some different relation.
- Having thus fully described the invention what I claim as new and desire to secure by Letters Patent is:
- 40 1. As an article of manufacture, a repair
- tip for shoes, comprising a toe cap having an inturned lower edge, a toe cap welt secured to the under face of said lower edge and extending outwardly beyond said toe cap, and means securing said inturned edge 45 and welt to each other.
2. In combination with a shoe vamp and a shoe welt secured thereto and extending therefrom, a shoe tip consisting of a toe cap having an inturned edge and a toe cap 50 welt secured to the under face of said in-turned edge, said toe cap welt being in alignment with said shoe welt.
3. In combination with a shoe vamp having an inturned edge and a shoe welt secured 55 to the under face of said edge and extending outwardly therefrom, a shoe tip consisting of a toe cap having an inturned edge and a toe cap welt secured to the under face of said edge and extending outwardly of the 60 toe cap, said toe cap welt aligning with and being contiguous with said shoe welt.
4. In combination with a shoe vamp having an inturned lower edge and a shoe welt secured thereto and extending outwardly 65 beyond said shoe vamp, a shoe repair tip consisting of a toe cap having an inturned edge and a toe cap welt secured to the under face of said inturned edge and extending outwardly beyond said cap, the rear edge 70 of said toe cap being secured to said vamp, and said welts being in alignment with each other.
5. The combination as specified in claim 4, and a half sole secured to both of said 75 welts.

Signed at Bridgeport, in the county of Fairfield and State of Connecticut this 20th day of January A. D. 1922.

NICOLA D'ANDREA.
